Des. 201,828
Patented Aug. 3, 1965

201,828

STAMP DISPENSING MACHINE

James H. Walker, Los Angeles, Calif., assignor of one-half to Leland L. Dills and one-half to Richard W. Callaway, both of Arcadia, Calif.

Filed Oct. 7, 1964, Ser. No. 82,068

Term of patent 14 years

(Cl. D52—2)

FIG. 1.

FIG. 4.

FIG. 2.

FIG. 3.

The undisclosed side of the stamp dispensing machine is substantially the same in appearance as the side shown.

I claim:

The ornamental design for a stamp dispensing machine, as shown and described.
